UNITED STATES PATENT OFFICE.

DANIEL WEBSTER CAMERON, OF ANTIOCH, NEBRASKA.

MATERIAL AND ARTICLE HANDLING APPARATUS.

Application filed March 12, 1921. Serial No. 451,915.

To all whom it may concern:

Be it known that I, DANIEL WEBSTER CAMERON, a citizen of the United States, and a resident of Antioch, in the county of Sheridan and State of Nebraska, have invented certain new and useful Improvements in Material and Article Handling Apparatus, of which the following is a specification.

The present invention relates in general to material and article handling apparatus and more particularly to apparatus of this character especially though not necessarily adapted for use in loading grain into cars, bins, cribs or the like.

15 The object of the invention is to provide a material and article handling apparatus of this character which will efficiently load the material upon the car or the like, which will uniformly distribute the load of the material over the area to be loaded and which is of simple and durable construction, reliable in operation and easy and inexpensive to manufacture.

Other objects and advantages of the invention reside in certain novel features of construction, combination and arrangement of parts which will be hereinafter more fully described and particularly pointed out in the appended claims, reference being had 25 to the accompanying drawings forming part of this specification, and in which:

Figure 1 is a view of the apparatus in use in loading a railway car, parts being shown in elevation and other parts being 30 shown in section for the sake of illustration;

Figure 2 is a plan view of the apparatus in one position, the top of the car being removed for the sake of illustration;

40 Figure 3 is a similar view of the apparatus in the opposite position;

Figure 4 is a detail view in transverse section taken approximately on line 4—4 of Figure 3, parts being broken away and parts 45 being shown in elevation for the sake of illustration;

Figure 5 is a similar view, partly in elevation and partly in section taken approximately on line 5—5 of Figure 2, parts being 50 broken away and parts being shown in elevation and in section for the sake of illustration;

Figure 6 is a detail view, in section, taken approximately on line 6—6 of Figure 5, the 55 associated structure being omitted.

Referring to the drawings wherein for

the sake of illustration the invention is shown in use with a railway car, the railway car being designated at R and being preferably of conventional construction. The 60 sides and bottom wall of the car define a container similar to that defined by like walls of a bin, crib or the like.

Longitudinal stringers 10 are arranged along and secured to the interior of each of 65 the side walls and extending between and retained on these stringers are a plurality of cross bars 11. These stringers and cross bars constitute supporting means for the instrumentalities to be hereinafter more fully 70 described.

A platform designated generally at 12 is arranged upon the supporting means and includes spaced and longitudinal angle bars 13 secured together by means of braces 14 75 or the like. Flanged rollers or wheels 15 are carried by the angle bars by means of suitable brackets 16, and these flanged wheels run upon the cross bars 11 whereby the platform is mounted for transverse 80 movement. The angle bars 13 include vertically extending portions 13^b and smooth horizontally extending portions 13^a which together constitute a way in which a bottom plate 17 is slidably mounted for longitudinal 85 movement, that is, the bottom plate 17 is movable at right angles or angularly with respect to the movement of the platform itself.

Mechanism is provided for moving the 90 platform transversely under the control of the operator and comprises the rack bar 20 having one end secured to the platform and extending exteriorly of the car. The rack bar 20 is preferably made up of a plurality 95 of sections 20^a suitably united by universal joints or couplings 20^b permitting the requisite movement, and as shown in Figure 2, the teeth of these sections are adapted to mesh with a drive pinion 22 fixed to a shaft 100

23 journaled in suitable bearings in the frame 24 and actuated by any suitable means which for the sake of illustration is shown as a hand crank 25 but it is to be understood that a motor or the like may be employed if desired. The movement of the platform is made uniform and precisely the same at both ends and throughout its length by means of sprocket chains 21 having their ends secured to the platform and run over 105 idle sprocket wheels 21^a carried upon suitable shafts 21^b. Mechanism is also provided

for imparting longitudinal movement to the bottom plate 17, and this mechanism includes a rack bar 26 fixed to the underside of the bottom plate and engaged by a pinion 27 keyed or otherwise secured to a shaft 28 journaled in suitable bearings 29 and actuated by means of a hand crank 30 or the like arranged at a point adjacent the hand crank 25.

10 Means is provided for delivering the material or article to the bottom plate and includes an elevator conveyor 35 of the endless type supported by the frame 24 and carrying the material to a horizontal conveyor 36 which extends from the elevator to within the car or bin being loaded. The horizontal conveyor delivers to a distributor head 37 the endless scrapers 36^a carrying the material along the bottom of the conveyor until 15 it drops therein. A delivery spout 38 is swiveled upon the distributor head 37 and may be turned to follow the platform 12 to deliver the material to the bottom plate 17 of the platform. The elevator 35 and horizontal conveyor 36 are driven from a motor 39 by suitable motion transmission means which preferably includes a belt 40 driven from the transmission shaft of the engine and driving a jack shaft 42 by means of a 20 pulley 41 over which the belt 40 runs. The jack shaft 42 is journaled in suitable bearings 43 arranged upon the frame 24. The jack shaft has fixed thereto a small pulley 44 which drives a pulley 45 fixed to the upper sprocket wheel shaft 46 of the elevator 35 by means of a belt 47. The endless scraper of the horizontal conveyor 36 is driven from the sprocket shaft 45 of the elevator by means of the belt 48 which runs over a pulley 49 fixed to one of the sprocket wheel shafts 30 of the horizontal conveyor and a suitable driving pulley 50 fixed to the sprocket wheel shaft 46 of the elevator.

Means is provided for discharging material from the bottom or bottom plate of the platform and includes a frame 55 mounted upon the top surface of the vertical portions 13^b of the angle bars 13. At the opposite ends of the frame, shafts 56 and 57 are journaled and carry sprocket wheels 58 and 59, respectively, upon which are mounted endless sprocket chains 60 carrying transverse scraper elements, preferably in the form of T-bars 61. These scraper elements are arranged at regular spaced intervals around the entire extent of the sprocket chains and during their travel they slidably engage the bottom plate 17 or such portion of the bottom plate as underlies these 50 scraper elements. The shafts 56 and 57 also carry rollers 62 which may be integrally formed with the sprocket wheels and which engage the top of the vertical portion of the angle bars 13, whereby the frame 55 may 60 be readily moved relative to the platform.

Means is provided for guiding the frame during its movement and for locking it in either of its positions and includes a bracket 63 having an aperture 63' therein adapted to be aligned with similar apertures formed 70 in the portion 13^b of the platform and a cotter pin or other form of locking pin 64 adapted to be extended through the aligned openings to lock the frame in either position.

75 Driving mechanism is provided for the endless scraper and includes a squared shaft 65 made up of a plurality of sections releasably coupled by means of coupling members 66. The shaft is journaled at one end in the bearing bracket 67 and is driven at this end by means of gearing 68 from the jack shaft 42. At its opposite end the shaft 66 is adapted to be slidably received in either of the squared sockets 69 or 70. These sockets 85 69 and 70 are provided in and extend through the sprocket wheel shafts 56 and 57, respectively, and it is to be understood that when the conveyor is in one of its positions the shaft is engaged in the squared 90 socket 69 of the shaft 56 and that when it is in its other position it engages in the squared socket of the shaft 67. In either event the squared socket serves to couple the shaft 65 to the sprocket wheel shaft and to 95 also support this end of the shaft.

In operation the elevator 35 picks up the material or articles being handled and carries them to the horizontal conveyor 36 from which they are delivered to the distributor head 37 and the delivery spout 38 then delivers the material upon the bottom plate of the platform 12. The scrapers 61 discharge the material endwise from the bottom plate into the bin or car being loaded. 100 As the loading operation progresses the platform is fed transversely or across the bin or car by turning the shaft 28 and the bottom or bottom plate is also moved longitudinally by turning the shaft 28 and in 105 all positions the endless scrapers constituted by chain 60 and scrapers 61 are continuously driven as the squared drive shaft 65 slidably extends through the socket of the sprocket shaft. The operation is thus continuous until one-half of the car has been loaded and during this continuous operation for this period the material is evenly distributed over this area of the car or bin. 110 When approximately one-half has been loaded, the endless scraper must be shifted from one extreme position that is in the position shown in Figure 2 to the position shown in Figure 3. This is easily done by disconnecting the shaft 65 from its squared 115 socket, releasing the locking pin 64 and moving the endless scraper along the platform from one end to the other and then recoupling the shaft and then reinserting the locking pin and the squared shaft. The op- 120 125 130

eration is then carried on as before with the exception that the bottom plate is now moved in the opposite direction. Previously it has been moved from the right to the 5 left and it is now moved from the left to the right. It is to be understood that the feeding or movement of the platform transversely varies the lateral point of discharge of the material into the bin or car and the 10 feeding or movement of the bottom plate varies the longitudinal point of discharge and as these movements are coordinated, the point of discharge is always controlled by the operator so that the material may be 15 controlled and uniformly distributed over the car or bin being loaded.

I claim:

1. In a material and article handling apparatus, supporting means, a transverse 20 movable platform carried by said supporting means and having a longitudinal movable bottom plate, mechanism for imparting transverse movement to said platform, mechanism for imparting longitudinal movement to said bottom plate, means for delivering the material to the bottom plate including an elevator, a horizontal conveyor leading from said elevator, a distributor head receiving the discharge of 25 said horizontal conveyor and a swivelled delivery spout carried by the distributing head and adapted to follow the transverse movable platform in its movements, means for driving said elevator and said horizontal 30 conveyor and means for discharging the material from the bottom plate including a pair of endless chains carrying spaced 35 scraper bars slidably engaged with the bottom plate.
2. In a material and article handling apparatus, supporting means, a platform carried by said supporting means and movable transversely thereof, mechanism including 40 a rack connected to the platform and a driving pinion meshing with said rack for imparting transverse movement to said platform, said platform having a longitudinally 45 sliding bottom plate, mechanism for imparting movement to said bottom plate, means for delivering the material to the bottom 50 plate, and means for discharging the material therefrom.

3. In a material and article handling apparatus, a transversely movable platform 55 having a longitudinally slidable bottom plate, means for delivering the material to the bottom plate including a swiveled delivery spout adapted to follow the platform in its movements, and means for discharging 60 the material from the bottom plate in all of its positions including endless chains and scrapers carried by said chains and having slidable engagement with said bottom plate.

4. In a material and article handling apparatus, a transversely movable platform 65

having a longitudinally slidable bottom plate, means for delivering the material to the bottom plate, and means for discharging the material from the bottom plate in all of its positions including endless chains and 70 scrapers carried by said chains and having slidable engagement with said bottom plate.

5. In a material and article handling apparatus, a transversely movable platform having a longitudinally slidable bottom plate, 75 means for delivering the material to the bottom plate, including a swiveled delivery spout adapted to follow the platform in its movements, and means for discharging the material from the bottom plate in all of its 80 positions.

6. In a material and article handling apparatus, a transversely movable platform having a longitudinally slidable bottom plate, mechanism for imparting transverse movement to said platform, mechanism for imparting longitudinal movement to said bottom plate, means for delivering the material to the bottom plate and means for discharging 85 the material therefrom. 90

7. In a material and article handling apparatus, a transversely movable platform including spaced and longitudinally extending angle bars, a bottom plate slidably carried by the horizontal portions of said angle 95 bars, means for delivering the material to the bottom plate, and means for discharging the material therefrom.

8. In a material and article handling apparatus, a transversely movable platform 100 having a longitudinally slidable bottom plate, means for delivering the material to the bottom plate of said platform, and means for discharging the material therefrom in all phases of its movement. 105

9. In a material and article handling apparatus, a movable platform having a bottom adapted to partake of movement angularly with respect to the platform, means for delivering the material to said bottom, and 110 means for discharging the material therefrom in its various positions.

10. In a material and article handling apparatus, a transversely movable platform including spaced and longitudinally extending angle bars, a bottom plate slidably carried by the horizontal portions of said angle bars, means for delivering the material to the bottom plate, and means for discharging the material therefrom including a frame 115 120 slidably mounted on the vertical portion of said angle bars, means for guiding the frame and for locking it in position thereon, spaced shafts journaled in said frame, endless chains driven from said shafts, spaced 125 scraper elements carried by said endless chains, and engageable with said bottom plate, and means for driving said shafts in either position of said frame.

11. In a material and article handling ap- 130

paratus, a transversely movable platform including spaced and longitudinally extending angle bars, a bottom plate slidably carried by the horizontal portions of said angle bars, means for delivering the material therefrom including a frame mounted on the angle bars, spaced shafts journaled in said frame and having squared sockets extending therethrough, endless chains driven from said shafts, scraper elements carried by said endless chains and engageable with said bottom plate, and means for driving said shafts in either position of said frame including a squared shaft adapted to be slidably received 15 in the squared sockets.

12. In a material and article handling ap-

paratus, a movable platform having a bottom adapted to partake of movement angularly with respect to the platform, means for delivering the material to said bottom, 20 and means for discharging the material therefrom including a frame movably mounted in said platform, spaced shafts journaled in said frame and having squared sockets, an endless scraper driven from the shaft and cooperated with said bottom to discharge the material endwise therefrom, and means for driving said endless scraper including a squared drive shaft adapted to be slidably engaged with the squared sockets 25 of said spaced shafts.

DANIEL WEBSTER CAMERON.
